UNITED STATES PATENT OFFICE.

ROY B. WEIMER, OF AKRON, OHIO, ASSIGNEE TO THE MILLER RUBBER COMPANY, OF AKRON, OHIO, A CORPORATION OF OHIO.

INFLATABLE TOY.

Application filed September 19, 1925. Serial No. 57,360.

This invention relates to toys made of rubber capable of inflation and which when so inflated simulate a living being.

The principal objects of the invention are:

- 5 the provision of a toy as above which may be cut from sheets of unvulcanized rubber and which when cured and inflated will have, in the case of a simulated human being, arms and legs in their proper relation; which 10 may have rubber coverings simulating clothing, and which may be easily and cheaply manufactured.

It is well known in this art that it is difficult to cheaply manufacture a toy simulating a human being from sheet rubber by a cutting process, and at the same time provide the toy with the requisite number of legs or arms, as the case may be. This invention contemplates a structure making the 20 above possible.

To this end the invention contemplates cutting a main or body compartment of the toy from two superimposed talc or soap stone dusted sheets of unvulcanized rubber with 25 a die having blunt edges. This cutting action is well known and unites the two sheets along the cut at the same time. This main or body compartment is to include as much of the figure as possible, the remaining arms 30 and legs, as the case may be, being cut as offshoots or supplemental compartments, each of which is connected to the main compartment by a conducting tube formed of the same sheets and at the same time. These 35 supplemental compartments are then folded or juxtaposed upon the main compartment until they occupy the proper relation thereto. They may be held in this position by either cement or an envelop enclosing both 40 main and supplemental compartments or both. The envelop may simulate clothing.

The accompanying drawings are illustrative of the principle involved.

In the drawings:—

45 Figure 1 is a side elevation of a completed toy.

Fig. 2 is a detail showing an arm and leg folded.

Fig. 3 is a plan view of the cut-out device.

50 Fig. 4 is a detail of the passageway between an arm and leg and the body portion.

Fig. 5 is a side elevation of the superimposed rubber sheets.

55 In the embodiment shown, two sheets of unvulcanized rubber are shown at 1 and 2,

calendered to the proper thickness and well dusted with talc or soap stone to prevent sticking. A die (not shown) having a blunt edge of a configuration indicated at 3 is used to cut through both sheets 1 and 2 upon a hard flat surface. This cutting process not only cuts the rubber sheets but secures the sheets together along the cut, which when cured becomes a permanent joint. All of this is well known in the art and no claim is 60 made thereto.

This cut out toy, which in the present case is to simulate a diving girl in a bathing suit, is shown to consist of a main or body compartment 4 forming the body, head and one leg of the girl, and supplemental compartments 5, 6 and 7 forming the two arms and other leg respectively. Each of these supplemental compartments is joined to the main compartment by means of a narrow 70 tube formed from the sheets 1 and 2, as at 8. These tubes allow air or other fluid blown into the main compartment through an aperture in the foot 9 to flow therethrough into the several supplemental compartments. 75

After vulcanization, to permanently unite the two cut out figures, the supplemental compartments are juxtaposed upon the body until the proper relation exists and then held 80 in this position by means of cement.

At 10 is shown an envelop cut from two unvulcanized sheets of rubber by a die and then vulcanized.

This envelop, which in the present case is 90 made to simulate a bathing suit, partially encloses the toy and assists in holding the arms and legs in position and at the same time covers up the cemented joints and the tubes 8.

I claim:

1. An inflatable toy comprising a main compartment simulating a human body, head, and leg, supplemental compartments simulating the other leg and both arms connected thereto and interiorly communicating therewith, said supplemental compartments having portions overlying the body portion of the main compartment, an envelope enclosing the body portion of the main compartment and overlying portions of the supplemental compartments only, and means for inflating the compartments. 100

2. An inflatable toy having a main compartment simulating a human torso, a head and one leg, two arms forming compart- 105

ments interiorly communicating with the shoulder portions of the main compartment and having parts superimposed thereon, a leg forming compartment interiorly communicating with the thigh portion of the main compartment and having a part overlying said thigh portion, and an envelope en-

closing said torso and the overlying portions, the head, arms and legs projecting beyond the envelope, said envelope holding the overlying parts in close juxtaposition, and means for inflating the compartments. 10

In testimony whereof I affix my signature.

ROY B. WEIMER.
